[57] CLAIM

The ornamental design for a screen door, substantially
as shown and described.

DESCRIPTION

FIG. 1 is a perspective view of a screen door showing
my new design;

FIG. 2 is a front view thereof with the rear view being
identical to that shown;

FIG. 3 is a top plan view thereof, with the bottom plan
view being the same as that shown; and

FIG. 4 is a right side view thereof, with the left side
view being the same as that shown.

Fig. 1.

Fig. 2.

Fig. 3.

Fig. 4.
